US00D912149S

(12) **United States Design Patent** (10) **Patent No.:** **US D912,149 S**
(45) **Date of Patent:** **** Mar. 2, 2021**

(54) **SIGN HOLDER**

(71) Applicant: **TIME'S SQUARE DISTRICT MANAGEMENT ASSOCIATION, INC.**, New York, NY (US)

(72) Inventor: **Louis Wuyi Lim**, Brooklyn, NY (US)

(73) Assignee: **Times Square District Management Association, Inc.**, New York, NY (US)

(**) Term: **15 Years**

(21) Appl. No.: **29/647,096**

(22) Filed: **May 9, 2018**

(51) LOC (13) Cl. **20-02**

(52) U.S. Cl.

USPC **D20/10**

(57) **CLAIM**

The ornamental design for a sign holder, as shown and described.

DESCRIPTION

FIG. 1 is a perspective view thereof;
FIG. 2 is a right elevational view thereof;
FIG. 3 is a left elevational view thereof;
FIG. 4 is a front elevational view thereof;
FIG. 5 is a rear elevational view thereof;
FIG. 6 is a top plan view thereof;
FIG. 7 is a bottom plan view thereof, and
FIG. 8 is a perspective view of the sign holder illustrating a sign attached thereto; and FIGS. 9-16 illustrate a design for a sign holder according to a second embodiment of the invention, and wherein
FIG. 9 is a perspective view thereof;
FIG. 10 is a right elevational view thereof;
FIG. 11 is a left elevational view thereof;
FIG. 12 is a front elevational view thereof;
FIG. 13 is a rear elevational view thereof;
FIG. 14 is a top plan view thereof;
FIG. 15 is a bottom plan view thereof; and
FIG. 16 is a perspective view of the sign holder illustrating a sign attached thereto; and
FIG. 17 is a perspective view thereof;
FIG. 18 is a right elevational view thereof;
FIG. 19 is a left elevational view thereof;
FIG. 20 is a front elevational view thereof;
FIG. 21 is a rear elevational view thereof;
FIG. 22 is a top plan view thereof,
FIG. 23 is a bottom plan view thereof; and
FIG. 24 is a perspective view of the sign holder illustrating a sign attached thereto.

The broken lines in the figures are for the purpose of illustrating environmental structure and form no part of the claimed design.

1 Claim, 15 Drawing Sheets
